UNITED STATES PATENT OFFICE.

VACLAV A. ADAMEC, OF CINCINNATI, OHIO.

FENDER.

1,160,030.

Specification of Letters Patent.

Patented Nov. 9, 1915.

Application filed April 5, 1915. Serial No. 19,275.

To all whom it may concern:

Be it known that I, VACLAV A. ADAMEC, a subject of the Emperor of Austria-Hungary, residing at Cincinnati, in the county of 5 Hamilton and State of Ohio, have invented certain new and useful Improvements in Fenders, of which the following is a specification, reference being had to the accompanying drawings.

10 This invention relates to certain improvements in fenders and it is an object of the invention to provide a device of this character having novel and improved means whereby a rescue is assured irrespective of 15 the position of the person struck.

The invention consists in the details of construction and in the combination and arrangement of the several parts of my improved fender whereby certain important 20 advantages are attained and the device is rendered simpler, less expensive and otherwise more convenient and advantageous for use, all as will be hereinafter more fully set forth.

25 The novel features of the invention will be carefully defined in the appended claims.

In order that my invention may be the better understood, I will now proceed to describe the same with reference to the accompanying drawings, wherein—

Figure 1 is a view in side elevation of a fender constructed in accordance with an embodiment of my invention, the coacting portion of the vehicle being indicated by 35 dotted lines; Fig. 2 is a view in top plan of the device as illustrated in Fig. 1, with the rear buffer omitted; Fig. 3 is a sectional view taken substantially on the line 3—3 of Fig. 1; Fig. 4 is an enlarged fragmentary 40 view partly in elevation and partly in section, illustrating certain details of the invention as herein included; Fig. 5 is a sectional view taken substantially on the line 5—5 of Fig. 4; Fig. 6 is a sectional view 45 taken substantially on the line 6—6 of Fig. 1; and Fig. 7 is a fragmentary view, partly in elevation and partly in section, illustrating the means for releasing the locking pawl herein embodied.

50 As disclosed in the accompanying drawings, F denotes the frame of a vehicle having depending from the forward extremity thereof the posts 1 positioned adjacent oppo-

site sides of the frame and terminating in close proximity to the surface over which 55 the vehicle may travel.

The lower end portions of the posts 1 are provided with the trunnions 2 to which are affixed the upstanding parallel arms 3 projecting a predetermined distance in advance 60 of the frame F and having secured thereto the base member 4 substantially V-shape in contour, with the apex thereof disposed outwardly and with its rear portion of a length in excess of the width of the frame F and 65 the supporting wheels carried thereby.

At substantially its axial center the member 4 has secured thereto, and rotatable about a vertical axis, a stellar wheel 5 having pivotally engaged therewith the rods 6, 70 one of said rods being rearwardly directed and operatively engaged with the crank 7 carried by the shaft 8 which will be herein-after more particularly referred to. The remaining rods 6 have their outer extremities operatively engaged at predetermined 75 points with the recoil member 9 overlying the outer free marginal portions of the member 4 and adapted to be moved inwardly when brought in contact with an object, such 80 inward movement of the recoil member terminating in a rotation of the stellar wheel 5 and a resultant rotation of the shaft 8.

Normally projecting beyond the member 4 is a frame 10 of a configuration substantially identical with that of the member 4 and said frame is operatively engaged with the arms 3 through the medium of the links 11 and with the trunnions 2 through the medium of the rock arms 12 loosely engaged 90 with said trunnions. One of said rock arms at its upper extremity is provided with a segmental rack 14 with which is engaged a pawl 15 carried by the shaft 7, hereinbefore referred to, and it will be readily perceived 95 that upon inward movement of the rod 6, said pawl 15 will be disengaged from the rack 14 whereupon the frame 10 will be capable of outward movement under the influence of the expandable members 16 interposed between the rock arms 12 and the brackets 17 depending from the frame F. It is to be observed that the outward movement of the frame 9 is sufficient to project 100 beyond the outer margins of the member 4, and should the object struck be a person

standing, serves to strike the lower extremities of the lower limbs of the person and assure his or her falling upon the member 4.

Pivotsly engaged as at *a* with the member 4 in close proximity to the apex or outer end thereof is the upstanding arm 18 of predetermined length and provided along its outer edge with the operating arm 19 of the latch 20 coacting with the segmental rack 21 suitably positioned upon the base member 1, and whereby said arm 18 may be normally maintained upon a predetermined rearwardly disposed incline. The upper extremity of the arm 18 has secured thereto a flexible strip or belt 22, the opposite extremity of which being suitably secured to the member 4 at a predetermined point adjacent the rear thereof.

I also find it of advantage to secure to the flexible strip or belt 22 at opposite sides thereof the nets 23 also secured to the member 4 and disposed on predetermined downwardly diverging planes, for a purpose which is believed to be self-evident.

Should a person be struck by my improved fender at the forward part thereof, it will be perceived that he or she by falling upon the flexible strip or belt 22 of the nets 23 will be directed thereby to the rear portion of the member 4 whereby the possibility of injury is substantially entirely eliminated.

Should a person be struck by the forward or apex portion of the member 4, the contact of the body with the operating arm 19 will disengage the latch 20 from the rack 21 whereby the arm 18 will move rearwardly and assume a horizontal plane and thereby offer no obstruction or hindrance to the rescue.

To further facilitate a rescue, especially when the body is brought in contact with the arm 18, I find it of advantage to employ the rods 24 positioned adjacent the outer or apex end of the member 4 and movable laterally thereof and in opposite directions, the inner or adjacent extremities of said rods being operatively engaged with the toggle 25 under control of the cam 26 secured to the lower extremity of the arm 18. By this arrangement, it will be perceived that upon rearward swinging movement being imparted to the arm 18, the rods 24 are forced outwardly. The arm 18 is adapted to be returned manually to its normal or upright position.

Positioned above the rear portion of the member 4 is the buffer 27 of any desired construction and serving in a manner and for a purpose which is believed to be self-evident.

From the foregoing description, it is thought to be obvious that a fender constructed in accordance with an embodiment of my invention is of a simple and comparatively inexpensive nature and is particularly

well adapted for use by reason of the convenience and facility with which it may be assembled, and it will also be obvious that my invention is susceptible of some change and modification without material departure from the principles and spirit thereof, and for this reason I do not wish to be understood as limiting myself to the precise arrangement and formation of the several parts herein shown in carrying out my invention in practice.

I claim:

1. A device of the character described comprising a member, a second member positioned therebeneath and mounted for movement relatively thereto, automatic means for projecting the second member outwardly relative to the first named member, means for normally holding the second member in a retracted position, and automatic means for releasing said holding means.

2. A device of the character described including a member, an arm projecting upwardly from said member adjacent the outer end thereof, a strip connecting the upper extremity of said arm and the rear portion of the member, and a fabric secured to said strip and to the member at opposite sides of the arm.

3. A device of the character described comprising a member, an upstanding arm pivotally engaged with the forward portion of the member, a flexible strip connecting the upper extremity of the arm and the rear portion of the member, and releasable means for normally maintaining the arm in substantially a vertical position.

4. A device of the character described comprising a member, an upstanding arm pivotally engaged with the forward end portion of the member, rods movable transversely of the member and adapted to project therebeyond, and means under control of the arm for moving said rods outwardly as the arm swings rearwardly.

5. A device of the character described comprising a member, a second member positioned beneath the first named member and capable of movement relatively thereto, automatic means for imparting outward movement to the second member, means for normally holding the second member in a retracted position, a recoil member overlying a free marginal portion of the first named member, and means under control of the recoil member for releasing the holding means.

6. A device of the character described including a member, a second member mounted for movement relatively thereto, automatic means for projecting the second member beyond the first named member, a rotatable member carried by the first named member, a recoil member overlying an outer marginal face of the first named member, an operative connection between the recoil

member and the rotatable member whereby said rotatable member is caused to move upon inward movement of the recoil member, holding means for normally maintaining the second member in a retracted position, and an operative connection between the holding means and the rotatable member whereby said holding means is released

upon inward movement of the recoil member.

10

In testimony whereof I hereunto affix my signature in the presence of two witnesses.

VACLAV A. ADAMEC.
